UNITED STATES PATENT OFFICE.

PETER A. FAIR, OF HELENA, MONTANA.

HUMIDIFIER.

1,135,445.

Specification of Letters Patent. Patented Apr. 13, 1915.

Application filed May 22, 1914. Serial No. 840,292.

To all whom it may concern:

Be it known that I, PETER A. FAIR, a citizen of the United States, residing at Helena, in the county of Lewis and Clark and State 5 of Montana, have invented new and useful Improvements in Humidifiers, of which the following is a specification.

The invention proposes to effect an improvement in the humidifying elements of 10 humidors, whereby a satisfactory self feeding device may be provided at a low cost.

It is an important object to provide a device of this character especially adapted to 15 serve as a partition in such a device as that shown in my copending application Serial 817,789, but which may also be utilized as a side or lining element in various forms of humidors.

It is also an object to give an improved 20 absorbent element by which water is distributed and exposed for diffusion through the air of a humidor.

In prior absorbent elements great difficulty has been experienced in securing 25 complete distribution of water throughout the body of the absorbent element after it has been used for a time. The capillary circulation is efficiently maintained in my device over a very long period.

30 A further object is to reduce the number of parts required in the device to enable the renewal of water and cleaning of the absorbent element.

An important aim of the invention is to 35 provide a device which may be incorporated in various forms of boxes to convert them into humidors, without requiring special construction.

Additional objects and advantages will 40 appear, some of which will be apparent from the following description, and from the drawings, in which,

Figure 1 is a side view of my humidifier. 45 Fig. 2 is a top view thereof. Fig. 3 is a similar view with the top removed. Fig. 4 is a detail of the absorbent element. Fig. 5 shows a top view of the device in a humidor. 50 Fig. 6 illustrates the use of the device as a partition. Fig. 7 is a cross section of the device.

There is illustrated a receptacle and wall element combined, comprising an outer side 10, an inner side 11 spaced in practice about one half an inch apart, or less, being connected by the bottom plate 12 and ends 13

formed in any desired manner from material similar to that of the sides, sheet zinc or copper being ordinarily employed. Somewhat nearer one end than the other a partition 14 is secured between the sides 10 and 11, stopping short of the upper edges of the sides, a water-tight junction being made between the partition, the sides and the bottom. The longer part of the side 11 on one side of the partition is provided with a multiplicity of apertures 15, and a lid element 16 is also provided, which may be foraminous also throughout its length. The shorter space between the partition and one end 13 is filled with water when in use.

An absorbent element 17 is provided, comprising a body portion 18, corresponding in form to the space 19 immediately behind the foraminous portion of the side 11 of the device, and an integral extension 20 connected 75 to the body 18 at its upper edge, adapted to be projected into the water space 21 at the opposite end of the device. The extension 20 may be termed a wick element while the body 18 may be designated the distributor. 80

It is a great advantage of this construction that no special wick mounting or connections are required, for the conduct of water from the wick to the distributor. Neither do special separate devices have to 85 be employed for the performance of their functions.

Another advantage lies in the simplicity and ease of formation of the wick and distributor, it being only necessary to obtain a 90 rectangular sheet of the necessary material corresponding to the size of the wick and distributor combined, and cut a slit 22 transversely of its lesser dimension beginning at one edge and stopping short at the other 95 opposite. I have discovered that asbestos sheeting forms a highly efficient material for this purpose, liable in a minimum degree to deterioration in capillary action and having the further advantage that it will not 100 decay.

By forming a small groove at opposite sides of a container my humidifier may be easily mounted in a safe manner, as suggested in Fig. 6, where the grooves are so 105 formed that the device is virtually a partition separating the cigar compartment from the space for pipes and tobacco.

It is an advantage of the device that when mounted at one side of the humidor it will 110

itself protect the adjacent side of the humidor from excessive moisture without requiring a special lining.

By omitting the perforations in the lid over the water receptacle, and snugly fitting the lid, liability of spilling of water from the device is obviated.

What is claimed:

1. In a humidor, a humidifying element
- 10 comprising closely spaced side walls, a bottom and ends, a vertical transverse watertight partition therein nearer one end than the other and stopping short of the upper edges, at least one side being foraminated throughout its longer part to one side of the partition, a removable lid snugly engageable over the device throughout its length, a distributor in the larger compartment, and a wick in the smaller connected to the distributor over said partition.
- 15
- 20

Copies of this patent may be obtained for five cents each, by addressing the "Commissioner of Patents, Washington, D. C."

2. In a device of the class described, a container, a transverse partition therein stopping short of the access side, a rectangular absorbent sheet corresponding in dimension one way to the container in the plane 25 of the partition, said sheet having a slit cut therein in the direction of said dimension extending from one edge but stopping short of the opposite edge, said sheet being disposed in the container, the partition being engaged in the slit, and a closure for the container.

In testimony whereof I have hereunto set my hand in presence of two subscribing witnesses.

PETER A. FAIR.
